UNITED STATES PATENT OFFICE

121,306

DESIGN FOR A KNIFE

Irving Rosenbloom, New York, N. Y.

Application May 20, 1940, Serial No. 92,467

Term of patent 3½ years

To all whom it may concern:

Be it known that I, Irving Rosenbloom, a citizen of the United States of America, residing in the city of New York, county of New York, and State of New York, have invented a new, original, and ornamental Design for a Knife, of which the following is a specification, reference being had to the accompanying drawing, forming part thereof.

Fig. 1 is a plan view of a knife, showing my new design.

Fig. 2 is an edge view thereof.

I claim:

The ornamental design for a knife, as shown.

IRVING ROSENBLOOM.
